Inventor:
Harold Brix,
By *Dynamforth, Les, Clinton, Wilkes,
Hobbs.*

UNITED STATES PATENT OFFICE.

HAROLD BRIX, OF CHICAGO, ILLINOIS, ASSIGNOR TO SHARP & SMITH, OF CHICAGO, ILLINOIS, A CORPORATION OF ILLINOIS.

SYRINGE.

Application filed March 28, 1925. Serial No. 19,036.

This invention relates to improvements in syringes and is here shown embodied in a syringe especially adapted for medical use; for example, for administering a local anesthetic.

One of the features of the invention is the provision of simple and easily operable means for fastening a detachable nozzle or needle to the syringe. My improved syringe may be cheaply made, is easy to operate, and is strong and durable.

Other features of my invention will appear more fully as I proceed with my specification.

In that form of device embodying the features of my invention shown in the accompanying drawings, Figure 1 is a view of the complete syringe in front elevation, Fig. 2 is a fragmentary view of the lower end of the same looking from one side, Fig. 3 is a view taken as indicated by the line 3 of Fig. 2, and Fig. 4 is a view of the stamping from which the finger is made that comprises a part of the means for holding the nozzle or needle in place.

As shown in the drawings, 10 indicates a cylinder of a syringe which may be made in the ordinary form as well known in the art. The upper end of the cylinder is provided with the usual rings or handles 11; and within the cylinder operates a piston of the usual form attached to one end of the piston rod 12 which is provided with the usual ring or handle 13 on the other end. The cylinder, piston, piston rod and handles thus described form no part of the present invention.

The lower end of the cylinder is provided with a tapered extension 14. 15 indicates a detachable needle or nozzle, the lower end 16 being pointed in the usual manner for insertion into the tissues. The upper end of the needle 15 is provided with an enlarged socket 17 having a tapered bore adapted to accommodate the tapered extension 14 when the needle is in place. The interior of the socket 17 and the tapered extension 14 have corresponding tapers so that upon slightly pressing the socket over the tapered extension a nice fit will be obtained. The socket 17 is provided with two flattened wings 18 to assist in putting the socket in place over the tapered extension and to provide means for rotating the socket slightly as will be explained more in detail hereinafter.

Fig. 4 shows a blank or stamping 19 preferably formed out of stiffened sheet material. This blank 19 comprises a strip 20 enlarged and rounded at one end as indicated by 21; said enlarged end 21 being provided with a round hole 22. From this stamping or blank 19 is formed the finger comprising a part of the means for holding the needle in place. In forming the finger the strip portion 20 is given two substantially right angle bends as indicated at 20^a and 20^b in Fig. 2, the extreme end of the finger then lying below the rounded end 21 and pointing inwardly toward the tapered extension 14 as indicated by 20^c. The tapered extension 14 is then inserted through the hole 22 and the finger is soldered in place as indicated by 23. It is obvious that other means may be provided for holding the finger on the tapered extension 14. The upper end of the socket 17 is provided with a substantially semi-circular lug 24, the under surface of which is slanted or beveled as indicated by 25.

In the operation of the device, the needle is put in place by slipping the socket 17 over the tapered extension 14. When this is done, the socket 17 is turned so that the lug 24 will clear the end 20^c of the finger 20. The socket 17 is then rotated (in a clockwise direction as viewed in Fig. 3) to swing the lug 24 over the end 20^c of the holding finger 20. The beveled under surface 25 of the lug 24 rides up on the end 20^c of the finger thus drawing the socket 17 firmly up in place on the tapered extension 14 thus holding the needle firmly and securely in place. To remove the needle the socket 17 is rotated in the opposite direction until the lug 24 clears the end 20^c of the finger 20 whereupon the socket may be slipped off of the tapered extension 14.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as possible in view of the prior art.

What I claim as new, and desire to secure by Letters Patent, is:

1. A syringe provided with a cylinder; a

1. A syringe provided with a cylinder; a tapered extension on the cylinder; a detachable needle having a socket with a tapered bore adapted to fit over the tapered extension; and means for holding said socket in place on said extension, said means comprising a holding finger formed from a flat strip of sheet material having a hole in one end, the tapered extension on the syringe extending through said hole and the finger being attached thereto, and a part on the socket adapted to engage said finger by rotation of said socket on said tapered extension to tighten said socket on said extension.
2. A syringe provided with a cylinder; a tapered extension on the cylinder; a detachable needle having a socket with a tapered bore adapted to fit over the tapered extension; and means for holding said socket in place on said extension, said means comprising a finger formed from a strip of sheet material, said strip being provided with a hole at one end, with the tapered extension of the syringe extending therethrough and attached to said finger, the other end of said strip of material being bent downwardly and inwardly toward said tapered extension, and a part on said socket adapted to engage the inwardly extending end of said finger by rotation of said socket to tighten said socket on said extension.
3. A syringe provided with a cylinder; a tapered extension on the cylinder; a detachable needle having a socket with a tapered

bore adapted to fit over the tapered extension; and means for holding said socket in place on said extension, said means comprising a finger formed from a strip of sheet material, said strip being provided with a hole at one end, with the tapered extension of the syringe extending therethrough and attached to said finger, the other end of said strip of material being bent downwardly and inwardly toward said tapered extension, and a beveled part on the socket adapted to engage the inwardly extending end of said finger.

4. A syringe provided with a cylinder; a tapered extension on the cylinder; a detachable needle having a socket with a tapered bore adapted to fit over the tapered extension; and means for holding said socket in place on said extension, said means comprising a finger formed from a strip of sheet material, said strip being provided with a hole at one end, with the tapered extension of the syringe extending therethrough and attached to said finger, the other end of said strip of material being bent downwardly and inwardly toward said tapered extension, and a beveled part on the socket adapted to engage the inwardly extending end of said finger upon rotation of said socket.

Witness my hand this 26th day of March,
A. D. 1925.

HAROLD BRIX.
